UNITED STATES PATENT OFFICE.

SOL S. SONNEBORN, OF BROOKLYN, NEW YORK.

SECTIONAL HIGH-POTENTIAL INSULATOR.

1,242,616.

Specification of Letters Patent.

Patented Oct. 9, 1917.

Application filed December 9, 1916. Serial No. 135,923.

To all whom it may concern:

Be it known that I, SOL S. SONNEBORN, a citizen of the United States, and a resident of Brooklyn, county of Kings, and State of New York, have invented certain new and useful Improvements in Sectional High-Potential Insulators, set forth in the following specification.

This invention relates to high-potential insulators of the condenser type, employed as bushings for insulating transformer leads and the like from what is usually a grounded, perforated barrier of conducting material through which the conducting lead must emerge and from which it must be insulated.

The object of the invention is to form an insulator of as simple, compact and economical construction as possible, and which provides protective features against high-frequency, high-potential oscillations, due to abnormal line surges as well as embodying an efficient design for the normal voltages which it is expected to sustain.

To these ends an important feature of the invention is to provide for relief without danger of puncture from abnormal stress produced by high-frequency oscillations, while at the same time employing features such as dielectric configuration conforming to the flow lines of dielectric stress between terminals, to the end that the full dielectric value of the air may be employed. The more particular object of the present invention is to attain the above advantages in an insulator, the insulating material of which is a suitable vitrified product such as porcelain. A still further object of the present invention is to obtain the aforementioned broad objects in a sectional insulator to the end that, in the unlikely event of a puncture between any of the condenser sections, the entire insulator may be restored to perfect condition merely by replacing the punctured section.

The above and more detailed objects of the invention will more fully be understood by reference to the embodiment of the invention described for illustrative purposes in the following specification and shown in the accompanying drawings, which form a part hereof, in which like characters designate corresponding parts in the figures and

in which Figure 1 is a sectional elevation and Fig. 2 is a fragmentary sectional elevation showing a modification.

In the illustrative embodiment of my invention I have shown an insulating high-potential bushing of the condenser type, built up out of three major coaxial cylindrical sections 1, 2 and 3, each in the embodiment of a comparatively simple vitrified porcelain structure. Alternating with these insulating sections, forming partitions, are two cylindrical sheet metal sheaths 4 and 5. Each section of insulating material going to make up the complete insulator A should first be completed and individually tested, then the assembling of the entire insulator may be effected.

The outer insulating section 1 may have a protecting bushing 6 of sheet metal spun about it, the bushing being completed except for the inturning of the lip 7 about the ledge 8. Next the sheath 4 is inserted from the top downward into the section 1 and is initially formed with an outwardly flaring skirt at its upper end. When inserted within the porcelain section 1, its lower end is spun outwardly to form the bottom out-flaring skirt 10. The outward spinning of the skirt 10 may be facilitated by the slitting of the bottom end of the sheath 4 or by cutting out triangular sections. Next the composite structure, comprising the bushing 6, the section 1 and the sheath 4 is slipped from the bottom upwardly over the intermediate section 2, which is formed with an out-flaring petticoat 11, counter-cut on its under side to receive the skirt 9. A cylindrical bushing 13 is then slipped over the protruding end 14 of the intermediate section 2. The inner sheath 5 is then slipped into the intermediate section 2 from the upper end, and its bottom end is then spun outwardly to form the out-flaring skirt 15 in a manner similar to the forming of the skirt 10. The sheath 5 then, with its out-flaring skirt 15, locks the parts so far assembled together. The inner sheath then, with its attached parts, is slipped upwardly from the bottom end over the central section 3, which is formed at the top with one or more petticoats 16 and 17, the lower petticoat being countersunk to accommodate the out-flaring outer skirt 18 of the sheath 5. The upper

portion of the central section may be provided with a knob 19 to receive the metal cap 20 and is centrally cored to receive the conducting bolt 21. A porcelain bushing 25 is then slipped over the bottom end of the central section 3 and it may be locked in place by a metal washer 26 and suitable nuts 27, applicable to the threaded ends 28 and 29 of the bolt 21, and serving the combined purposes of maintaining the complete structure assembled, relieving electro-static stress and providing ready means for electric connections. Although I have described the formation of the skirts such as 9, 10, 15 and 18 by spinning out a flange from the integral metal of the sheath, it is to be understood that this is merely a preferred method and that the invention covers broadly sheaths having skirts formed in any convenient manner, and by no means of necessity in the form of an outwardly spun flange forming an integral part with the remainder of the sheath.

As a modification of the bushing 25, which is centrally, cylindrically perforated, a cup-shaped bushing 26 may be substituted by slightly shortening the central section 3, as shown in the modification 30.

When in use, this structure is adapted to combine air and porcelain as its insulation above the ledge 8 and porcelain and oil below the ledge 8, inasmuch as in general use the portion of the insulator below the ledge 8 projects usually within the oil filled metal housing of some structure such as a transformer, so that the oil level is above the outstanding skirts such as 10 and 15. By this provision an arc-over from one of the skirts such as 10 or 15 to the bushing 6 is therefore snuffed and the oil self-healing immediately upon its cessation. The breakdown distance from the ledges 15 and 10 under the conditions of service is intended to be less than that from any of the outer parts of the insulator.

It is of course to be understood that the composite insulator is not limited to the exact number of parts or to the exact configuration of parts illustrated. The arrangement of the metal cap, washer, sheaths and bushing, and the configuration of porcelain barriers is such as to relieve all local tensions directly between the porcelain partitions, so that the combined insulating effect of the porcelain is rendered approximately proportional to its total thickness. The exposed surfaces of the petticoats are intended to be a compromise between protection against surface leakage and positioning along the flow lines of static stress.

What I claim and what I desire to secure by United States Letters Patent is:

1. A high-potential, insulating bushing of the condenser type comprising a plurality of separable nesting cylindrical sections of

insulating material; and one or more cylindrical metal sheaths alternating with said sections, one said sheath having an outwardly flaring skirt at each end.

2. A high-potential insulated lead-in bushing for such devices as transformers comprising a plurality of separable coaxial nested sections of insulating material; a metallic sheath located between two of said nested sections to give a condenser effect; and a conductor extending axially through said sections and having at each end a radially extensive conducting member substantially in the form of a solid of revolution, both of which serve as electrostatic stress distributors and at least one of which maintains the assemblage of said separable sections.

3. A high-potential insulator comprising a plurality of separable coaxial nested sections; and a metallic sheath located between each pair of adjacent sections, both ends of said sheath having an outwardly flaring skirt.

4. A high-potential insulator comprising a plurality of separable coaxial nested sections; a metallic sheath located between each pair of adjacent sections, both ends of said sheath having an outwardly flaring skirt; and end sections of insulating material of enlarged diameter insulating said flared ends in an axially outward direction.

5. A high-potential insulating bushing of the condenser type comprising a plurality of separable cylindrical sections of insulating material; a metallic condenser-sheath between two adjacent sections; the outer section having a circumferential supporting ledge; and a sheet metal sheath located as a combined mechanical protector and electrostatic stress distributor about said outer section including said supporting ledge.

6. A high-potential insulating bushing of the condenser type comprising a plurality of nested individual cylindrical sections of insulating material; a metallic sheath located between each two adjacent sections; at least one of said metallic sheaths having a portion at one end outwardly flared and forming both a flange mechanically tending to hold a plurality of said sections in assemblage and an electric relief member.

7. A high-potential insulating bushing comprising a major section of cylindrical contour having at its top one or more outwardly flaring petticoats and a dependent tubular sleeve; a metallic sheath inclosing said tubular sleeve; a second cylindrical portion of insulating material nested about said metallic sheath; and means for holding said parts in assembled relation.

8. A high-potential insulating bushing comprising one section having one or more outwardly flaring petticoats and one or more tubular portions; one or more tubular sec-

tions of insulating material, each nested about the tubular portion of another section; and a metallic condenser sheath located between one or more pairs of adjacent sections of insulating material and having an outwardly flaring skirt conforming in configuration to one face of one of said petticoats; and means for holding the parts in assembled relation comprising an axial conductor.

10

In witness whereof I have signed my name to this specification, this 8th day of December, 1916.

SOL S. SONNEBORN.
